UNITED STATES PATENT OFFICE.

FREDERICK D. JONES, OF LOS ANGELES, CALIFORNIA.

DESIGN FOR A CRAYON-HOLDER.

SPECIFICATION forming part of Design No. 33,770, dated December 25, 1900.

Application filed October 26, 1900. Serial No. 34,514. Term of patent 14 years.

To all whom it may concern:

Be it known that I, FREDERICK DILLWYN JONES, a citizen of the United States, residing at Los Angeles, in the county of Los Angeles and State of California, have invented and produced a new and original Design for Crayon-Holders, of which the following is a specification, reference being had to the accompanying drawings, forming part thereof.

Figure I is a perspective view of a crayon-holder, showing my new design. Fig. II is a plan of a crayon-holder, showing my new design. Fig. III is an end elevation of the same.

As shown in the drawings, the leading or material features of my design consist in a series of flutes and grooves *a b*, and a raised

edge bead *c* on the top of the body *d* of the attachment. The flutes, grooves, and edge bead extend longitudinally of said body *d*.

Having described my invention, what I claim as new, and desire to secure by Letters Patent, is—

The design for a crayon-holder as herein shown and described.

In testimony whereof I have signed my name to this specification, in the presence of two subscribing witnesses, at Los Angeles, California, this 18th day of October, 1900.

F. D. JONES.

Witnesses:

JAMES R. TOWNSEND,
JULIA TOWNSEND.
